SHEET DELIVERY APPARATUS

Hobart W. Bruker, Bordentown, N. J., assignor to
 George W. Swift, Jr., Inc., Bordentown, N. J.,
 a corporation of New Jersey

Application March 19, 1945, Serial No. 583,565

4 Claims. (Cl. 271—69)

1

In the manufacture of corrugated paperboard, the machines which cut the continuously traveling web of paperboard into blanks of desired length are customarily provided with traveling belts or like conveyors which deliver the cut blanks successively from the machine, after which the blanks pass to a suitable takeoff point located at the end or side of the machine, whichever may be the more convenient. It is usually desired to run the web through the cutoff machine at a speed as high as practical, and the conveyor mechanism usually runs at a surface speed nearly double that of the web, with the result that the conveyor mechanism ejects the cut blanks at a high velocity which may be of the order of 600 to 800 ft. per minute. The ejected blanks usually pass to a receiving stand, truck or conveyor from whence they are conducted to the next succeeding operation, and if ejected at this high speed they are likely to bounce around out of proper position and relation, requiring extra labor to reposition or realign them properly with respect to each other. The blanks must be delivered without imposing substantial frictional, bending or crumpling stresses upon them, since the paperboard material otherwise may be injured, and excessive shocks or strains in the mechanism also should be avoided.

The primary object of the present invention is to provide a mechanism which will operate smoothly and reliably to slow down the velocity of the successively delivered relatively stiff and unbendable blanks under the above conditions of operation, and cause them to be gently and accurately deposited without injury at the desired point of delivery. While the invention has been evolved specifically for use in connection with the delivery of corrugated paperboard sheets as above described, it should be understood that it may be applied to the delivery of other sheets in so far as the operating conditions and requirements may be analogous, and within the scope permitted by the prior art.

Further objects and advantages of the invention will be in part obvious and in part specifically referred to in the description hereinafter contained which, taken in conjunction with the accompanying drawings, discloses a preferred form of apparatus capable of operating in accordance with the invention; such disclosure, however, should be considered as merely illustrative of the principles of the invention in its broader aspects. In the drawings—

Fig. 1 is a longitudinal sectional view, somewhat diagrammatic, showing the invention as applied to the delivery end of a cutoff machine.

Fig. 2 is a simplified schematic view illustrating the action of the slow-down mechanism shown in Fig. 1.

2

At the left of Fig. 1 I have shown in simplified form, the delivery end of a cutoff machine of the character above described, having a pair of rotary cutoff knives 1 and 2 between which the continuous web 3 of paperboard is continuously fed, to cause the web to be severed into a series of successive blanks 4, 4a of the desired length. To withdraw the blanks from the path of travel of the web, an appropriate conveyor mechanism is provided, which is indicated in Fig. 1 as consisting of an appropriate number of upper conveyor belts 5 running around guide pulleys 6, 7 and 8, and lower conveyor belts 9 running around pulleys 10 and 11. Since the above parts may be constructed and driven in manner well known to the art, they need not be described at greater length. The shaft 12 may be understood as being positively driven in appropriate manner (not shown) to operate the belts at the desired surface speed, and as previously stated the surface speed of the conveyor belts above described is substantially higher than the surface speed of web 3, so that a substantial gap is formed between successive blanks ejected from between the belts 5 and 9.

In accordance with the present invention I provide on opposite sides of the path of travel of the sheets ejected by the conveyor above described, rollers or equivalent sheet retarding devices which are disposed on opposite sides of the path of travel of the advancing blanks projected forwardly by the conveyor, and which are at all times positively spaced from each other a distance sufficient to prevent a blank from being positively gripped between such sheet-retarding devices, so long as the blank is engaged between and is being forwardly projected by the belts 5 and 9 of the conveyor. Thus so long as a blank is being positively fed forward by the conveyor, it may pass between the sheet retarding rollers or the like without any substantial retarding or buckling effect in the machine which might tend to buckle or otherwise injure the blank, but as soon as any given blank has advanced sufficiently to free it from engagement with the above mentioned conveyor, said blank is caused to tilt downwardly sufficiently to bring its opposite surfaces into substantial frictional engagement with the blank retarding rollers or the like which are disposed on opposite sides of the path of travel of the blanks as above mentioned. Under these conditions a substantial and progressively effective retarding effect is produced on the advancing blank, which markedly reduces its velocity of travel as finally ejected from the slow-down mechanism above briefly described. In this way it has been found that the forward velocity of the ejected blanks, even though they may be traveling at a speed of the order of 800 ft. per minute, when ejected

from the conveyor above mentioned, may be smoothly and reliably reduced to almost zero forward speed if desired, with the result that the ejected blanks drop gently down onto the table, truck, conveyor or the like which is used to collect them at the point of final delivery. Also each successive blank will be accurately positioned when deposited as above described, without shock or bouncing troubles as heretofore encountered.

Particularly when the blanks are being ejected from between the conveyor belts 5 and 9, at very high speeds as above described, I prefer to space the above mentioned slow-down rollers or the like a distance from each other, which will cause them to have a light frictional engagement with the opposite surfaces of each blank while the latter is still being projected forwardly by the conveyor. At slower speeds the distance between the slow-down rollers may be somewhat greater than the thickness of the blanks, but at higher speeds more accurate results will be secured as to ultimate positioning of the delivered blanks if the aforesaid light frictional engagement is maintained. Without this light frictional engagement there will be an instant between the time when the blank is projected forwardly by the conveyor and the time when it tilts into substantial frictional engagement with the slow-down rollers, during which instant the blank is without substantial restraint or guidance, and at the higher speeds the blanks may move somewhat irregularly by their own momentum during this instant, unless the above light frictional engagement is maintained. However this frictional engagement should be very light, until the blanks tilt into more positive engagement with the slow-down rolls as above described, in order to prevent buckling or other injuries to the blanks.

In the embodiment of the invention shown in Fig. 1 the slow-down mechanism includes a lower transverse roller 13 carried by a cross shaft 14, which roller is positively driven at a surface speed substantially slower than that of the conveyor belts 5 and 9 previously mentioned, the roller 13 operating in conjunction with an upper transverse idler roller 15 carried by a cross shaft 16. The rollers 13 and 15 are at all times positively spaced from each other, a distance great enough to prevent positive gripping of the blank 4a between the rollers, so long as such blank is traveling in the plane of the adjacent surfaces of belts 5 and 9. Thus so long as the blank is being positively advanced at high speed by the conveyor above described, such blank travels without substantial buckling or retarding effect between the rollers 13 and 15. But as soon as the blank has been projected beyond the conveyor constituted by belts 5 and 9, it is caused to tilt from the dotted position shown in Fig. 2, into the inclined position shown in the full lines of Fig. 2, in which latter position it engages with substantial pressure against the adjacent surfaces of the rollers 13 and 15.

In the illustrated form, this tilting movement is produced by the weight of the part of the blank which has passed beyond the rollers 13 and 15. Under these conditions the roller 13 exerts a continuous and positive retarding effect on the forward travel of blank 4a, as does also the roller 15 which as above stated is an idler roll, but which roll is caused to be rotated by roller 13 through the medium of the frictional engagement of the surfaces of blank 4a with rollers 13 and 15. Thus as the blanks continue

to travel between rollers 13 and 15 after being released from engagement with the conveyor constituted by belts 5 and 9, the forward velocity of the blanks becomes reduced to an amount equal to the surface speed of roller 13, which speed as above mentioned may be made very low if desired, so that the sheets drop gently down upon an appropriate receiving structure, whereon they will be accurately positioned.

- 10 As above mentioned the speed of travel of the blanks 4a is substantially higher than the speed of travel of web 3, so that the blanks successively ejected from between the conveyor belts 5 and 9 have substantial gaps between them. Thus when 15 a given blank is being slowed down between rollers 13 and 15 as above described, the next succeeding blank which is still moving at high velocity will not catch up on and collide with the more slowly moving blank ahead of it.
- 20 In the form of the invention under discussion the roller 13 is driven from the main drive of the machine through a sprocket 18 on shaft 12 and chain 20 which engages a sprocket 21 on an auxiliary cross shaft 22. A further sprocket 23 25 on shaft 22 is connected by a chain 24 to a sprocket 25 on the shaft 14 which carries the positively driven slow-down roller 13 above described. If desired the speed of the roller 13 30 may be adjusted by appropriate speed changing devices such as sprockets of different ratios or other more easily adjustable speed changing devices (not shown) which are well known in the art.

- 35 In the form shown the cross shaft 16 which carries the upper idler slow-down roller 15, is supported by bell crank levers 26 (Fig. 1) at the sides of the machine, which levers are pivoted about short studs 27 at the corresponding sides of the machine. To positively space the rollers 40 13 and 15 the proper distance from each other, as is highly important to satisfactory operation, each of the arms 26 is provided with an adjustable screw 28 (Fig. 1) which rests against a block 29 rotatably mounted in the main side frame of 45 the machine, and adjustable by means of a hand wheel 30 to position any one of its four plane faces underneath the screw 28. This particular arrangement is convenient for use in operating upon corrugated paperboard of various customarily used thickness, so that if the screw 28 be properly adjusted to secure the correct spacing of rolls 13 and 15 for one of these standard thicknesses, the block 29 may be readily shifted by hand wheel 30 to adjust the spacing of rollers 50 13 and 15 to the proper amounts for paperboards of other thicknesses frequently required. The blocks 29 may be mounted on a common shaft 31 connected to hand wheel 30 and of course refined adjustments of the screws 28 may be 55 made as needed at any particular time.

- 60 The mechanism is preferably arranged to permit the rollers 13 and 15 to spread apart relatively widely whenever a splice in the sheets of the blank creates an abnormal thickness of material which must be passed between rollers 15 and 13. In the particular form shown the weight of the roller 15 tends to hold the latter at the normally correct spacing from roller 13, and a spring 32 is provided for each of the screws 28 65 to hold the latter yieldingly against the blocks or stops 29. In the particular form shown, the spring 32 encircles a bolt 32a which passes loosely through a lug 32b fixed to the lever 26, and also passes loosely through a lug 32c carried by 70 the frame of the machine, spring 32 being com-

pressed between the head of bolt 32a and lug 32b so as to yieldingly urge lever 26 and roller 15 to swing in a clockwise direction as the parts appear in Fig. 1, until the screws 28 rest against their respective blocks 29. A stop nut 32d on bolt 32a holds the spring 32 under compression as aforesaid, and may be adjusted to regulate the amount of compression in said spring. But whenever an abnormal thickness of material reaches the rollers 13 and 15, the upper roller 15 will lift temporarily, sufficiently to permit the material to pass through without injury to the blank or to any of the parts of the machine. After the abnormal thickness has passed the rollers, the upper roller 15 resumes its normal position in which it remains correctly spaced from roller 13 for the particular normal thickness of blank which is then passing through the machine.

In the illustrated embodiment a table 17 is shown at the right of Fig. 1 as being located in a position appropriate to receive the blanks successively ejected from between rollers 13 and 15, and an appropriate transverse stop member 18 may be employed if desired, and positioned whenever desired longitudinally of the machine to limit the forward travel of the ejected blanks.

The machine will usually require no adjustment of the spacing of the slow down rollers from the conveyor to conform to blanks of different lengths; in other words blanks of substantially different lengths may be slowed down satisfactorily without shifting the slow-down rollers toward or from the conveyor.

While the invention has been disclosed as carried out by mechanism of the above described specific construction, it should be understood that changes may be made therein without departing from the invention in its broader aspects, within the scope of the appended claims.

I claim:

1. Sheet delivery apparatus of the character described including means for successively and positively advancing a series of relatively stiff and unbendable blanks, and a slow-down mechanism located beyond the delivery end of said blank advancing means, said mechanism including transverse rollers disposed on opposite sides of the path of travel of blanks advanced by said advancing means, means at all times spacing said rollers a distance great enough to prevent the blanks from being positively gripped between said rollers while in engagement with said blank advancing means, said rollers being rotatable at surface speed less than the speed of feed of said advancing means, said apparatus being constructed and arranged to cause the blanks projected between said rollers by the blank advancing means to tilt into more positive engagement with the adjacent surfaces of said rollers after passing beyond said advancing means, to slow down the velocity of travel of the blanks ejected from between said rollers.

2. Sheet delivery apparatus of the character described including means for successively and positively advancing a series of relatively stiff and unbendable blanks, and a slow-down mechanism located beyond the delivery end of said blank advancing means, said mechanism including a transverse roller disposed on one side of the path of travel of blanks advanced by said advancing means, said roller being driven at a speed less than the speed of feed of said advancing means, and a transverse idler roll disposed on the opposite side of the path of travel of blanks advanced

by said advancing means, means at all times spacing said rollers a distance great enough to prevent the blanks from being positively gripped between said rollers while in engagement with said sheet advancing mechanism, said apparatus being constructed and arranged to cause the blanks projected between said rollers by the blank advancing means to tilt into more positive engagement with the adjacent surfaces of said rollers after passing beyond said advancing means, to cause said rollers to slow down the velocity of travel of the blanks ejected from between said rollers.

3. Sheet delivery apparatus of the character described including means for successively and positively advancing a series of relatively stiff and unbendable blanks, and a slow-down mechanism located beyond the delivery end of said blank advancing means, said mechanism including a transverse roller disposed on one side of the path of travel of blanks advanced by said advancing means, means for positively driving said roller at a surface speed less than the speed of feed of said advancing means, a transverse blank retarding member disposed on the opposite side of the path of travel of blanks advanced by said advancing means, means at all times spacing said retarding member from said roller a distance great enough to prevent the blanks from being positively gripped between said roller and said blank retarding member while in engagement with said sheet advancing means, said apparatus being constructed and arranged to cause the blanks projected between said rollers by the blank advancing means to tilt into more positive engagement with the adjacent surfaces of said rollers and said sheet retarding member after passing beyond said advancing means to slow down the velocity of travel of the blanks ejected from between said roller and said blank retarding member.

4. Sheet delivery apparatus of the character described including means for successively and positively advancing a series of relatively stiff and unbendable blanks, and a slow-down mechanism located beyond the delivery end of said sheet advancing means, said mechanism including transverse blank retarding members disposed on opposite sides of the path of travel of blanks advanced by said advancing means, means at all times spacing said blank retarding members a distance great enough to prevent the blanks from being positively gripped between said retarding members while in engagement with said sheet advancing means, said apparatus being constructed and arranged to cause the blanks projected between said blank retarding members by the blank advancing means to tilt into more positive engagement with the adjacent surfaces of said retarding members after passing beyond said advancing means to slow down the velocity of travel of the blanks ejected from between said retarding members.
